UNITED STATES PATENT OFFICE

125,943

DESIGN FOR A COMBINATION WINDSHIELD SERVICE CABINET AND GASOLINE PUMP OR THE LIKE

Lawrence V. Shepherd, Van Nuys, Calif.

Application December 3, 1940, Serial No. 97,017

Term of patent 14 years

To all whom it may concern:

Be it known that I, Lawrence V. Shepherd, citizen of the United States and residing at 6958 Woodman Avenue, Van Nuys, Los Angeles County, California, have invented a new, original, and ornamental Design for a Combination Windshield Service Cabinet and Gasoline Pump or the like, of which the following is a specification, reference being had to the accompanying drawing, forming part thereof.

The figure is a perspective view of a combination windshield service cabinet and gasoline pump, showing my new design. The dominant features of my design consist in the portions shown in full lines in the drawing.

I claim:

The ornamental design for a combination windshield service cabinet and gasoline pump or the like, substantially as shown and described.

LAWRENCE V. SHEPHERD.
